TERNSTEDT MANUFACTURING COMPANY, OF DETROIT, MICHIGAN, A CORPORATION
OF MICHIGAN

REMOTE CONTROL LOCK

Application filed March 13, 1925. Serial No. 15,174.

This invention relates to a remote control for latches, and is especially adapted for automobile door latches, wherein it is desired to control the latch from a remote point which enables the occupant to open the automobile door without leaning forward in the seat, as is the case with the latch controls now most generally used.

The object of the invention is to provide—
10 first, a detachable connection between the latch unit and the actuator which permits the easy assembly of the parts and which enables the manufacturer to ship the latch, draft member and actuator separately. The de-
15 tachable connection may be very easily in-
stalled with a minimum amount of labor.

The second object is to provide a lost motion connection between the latch and the actuator. With such a lost motion connection
20 it is possible to actuate the latch independ-
ently of the remote control and the draft connections which connect the actuator with the latch proper.

Thirdly, it is the object to provide a re-
25 motely located independent actuator which is controlled by a rotary spindle that can pro-
trude thru the garnish moulding of the car.

Another feature is the provision of means
30 to prevent rattling between the rotary spin-
dle and the slide carried by the actuator
plate, and to hold the slide of the remote ac-
tuator from moving back and forth.

In the drawings:

Fig. 1 is a side elevation of a latch and a
35 remote control therefor.

Figs. 2, 3, 4 and 5 are sections taken on
the line 2—2, 3—3, 4—4, and 5—5 of Fig. 1
respectively.

Fig. 6 is a detail in perspective of the draft
40 member.

Fig. 7 is a detail in perspective of the slide.

Fig. 8 is a detail in perspective of one end
of the sliding bolt.

Fig. 9 is a section on the line 9—9 of Fig. 1.

The lock comprises a casing *a*, which slid-
ably supports the sliding bolt *b*. A coil
spring *c* bears against the struck-out ear *d*,
carried by the bolt for projecting the same
from out of the casing in the position shown
50 in Fig. 1. The roll-back *e* and the night-

latch *f* are other elements of the lock which are of standard construction and form no part of this invention. The inner end of the sliding bolt is provided with the struck-up lug *g*, the upper portion of said struck-up lug being twisted about the axis of the lug and inclined at an angle to the longitudinal axis of the sliding bolt to provide a head, as clearly shown in Fig. 8.

A draft member *h* is provided at one end 60 with a slot *i* which is arranged to engage over this struck-up lug carried by the sliding latch bolt. To assemble the draft member to the latch, it is necessary to tilt the draft member so that the slot *i* will pass 65 over the twisted head of the lug. The draft member can then be partially rotated and engaged over the lower portion of the lug when returned to the straight line position, or in other words, to the position which is 70 parallel to the longitudinal axis of the bolt. The twisted portion of the lug serves as a head to prevent the accidental displacement of the draft member or disconnection between the draft member and bolt. 75

At a remote point from the latch an actuator plate *k* is located and the vertical rotary spindle *m* is journaled in said plate, the lower portion of said rotary spindle being bowed out to form the crank portion *n*. A 80 coil spring *o* is engaged about the spindle and exerts a pressure on the spindle to urge the same in a clockwise direction, as viewed from below in Fig. 1. The actuator plate is grooved as at *p*, and in this groove is slidably supported the actuator slide *r*. This slide as shown in Fig. 7, is provided with the abutment *s*, a struck-out ear *t* and the fairly wide slot *u*. The draft member *h* is provided with the foot *v* which is under-cut as 85 at *w*, and the same may be connected to the slide by tilting the slide and inserting the foot *v* and the draft member sideways into the slot *u*, which engages the foot under the slide. The actuator may now be partially rotated to bring the same into a straight line position with the draft member and the sliding bolt. The foot of said draft member will now be caught under the slide and the 90 cutaway portion of said draft member per-

mits the draft member to be projected up through the slot *u*, and the movement of the slide will impart a corresponding movement to the draft member.

- 5 As the rotary spindle is rotated in a counter clockwise direction, as viewed from below in Fig. 1, the crank portion of the spindle will engage the abutment *s* carried by the slide and move the slide to the left, which will move the latch bolt or retract the same through the draft member *h*. The spring *e* in the latch casing will again project the bolt when the handle *x* secured to the vertical spindle is released. This spring will cause the abutment *s* to bear against the crank portion of the spindle and the coil spring *o* secured to the spindle exerts a pressure thereon to bind the crank portion of the spindle against the struck-up ear *t*. It will thus be seen that
- 10 20 the vertical spindle is held tightly between the abutment *s* and the ear *t*, which therefore prevents any rattling of the actuator, and prevents the slide moving back and forth.

The draft member *h* may be connected to 25 the actuator or sliding bolt by the detachable connection as described. This permits the actuator and latch unit to be connected together when assembled in the automobile body and enables the manufacturer of the 30 latch to ship the actuator, lock and draft member separately, the same being assembled by the body manufacturer when the latch and actuator are installed in the body.

The slot *i* at the end of the draft member 35 provides a lost motion connection between the sliding bolt and draft member. This allows the sliding bolt to be actuated or retracted independently of the actuator unit and draft member and when the said latch is actuated independently the draft member 40 remains stationary, the lug *g* being permitted to slide freely in the slot *i*. The spring *o* which exerts a pressure on the slide provides sufficient friction between the slide 45 and the groove *p* to prevent the draft member and slide from being moved when the latch is actuated independently of the remote control. But this force is slight, and is easily overcome when the vertical spindle is actuated to operate the latch.

50 Preferably, we set the actuator unit and the latch unit in the latch board and do not cut out the intermediate portion of the latch board between the two units. This will cause the draft member *h* to be bowed out, as shown in Fig. 9, thereby preventing the draft member 55 from rattling at the point where it is connected to the slide and to the bolt. Also this provides a slight amount of friction 60 which resists the rectilinear movement of the draft member.

65 As described, the draft link *h* has a slot *i* and pin *g* connection with the latch, and has a somewhat similar connection with the control member, namely, the foot *v* with the un-

dercut portion *w* which can be fitted into the slot *u* of the control member slide. These connections are quickly detachable connections between the draft member and the control member and the latch member. These 70 are very useful in assembly, and enable parts to be shipped and handled separately. This quickly detachable connection either to the control member or the latch member is essentially a hooking action, as the parts may be 75 easily hooked up by simply putting them together and effecting a relative sliding movement between them. We have therefore identified this quickly detachable connection in some of the claims by this relative sliding 80 movement and in others of the claims by referring to it as a hooking action.

What we claim is:

1. In a remote control latch for automobile bodies, the combination of a latching unit 85 provided with a bolt retractable from the outside of the door, a remote actuator, a reciprocable draft bar connection between said bolt and actuator, and a quickly detachable connection of the pin and slot type between 90 the draft connection and bolt and remote actuator.

2. In a remote control latch, the combination of an actuator, a latching unit which includes a casing, a sliding bolt supported therein and provided with a lug, the head of said lug being at an angle to the longitudinal axis of the bolt, a draft member provided with a slot at one end engaging over the lug and held from being disconnected with the 100 bolt by the head of the lug but which permits the draft member to be disconnected from said bolt by partially rotating the draft member to allow the slot to register with the twisted head of the lug, said draft member 105 being connected to the actuator to connect the actuator and sliding bolt together.

3. In a remote control latch for automobile bodies, the combination of a latching unit positioned upon the inside of the door and 110 provided with a sliding latch bolt, a rigid draft member connected to said latch bolt, a remotely located independent actuator unit comprising an actuator plate, a vertical spindle journaled therein, and motion translating means engaging the rotary spindle 115 and connected to the rigid draft member for converting the rotary motion of the spindle to a reciprocating movement of the draft member.

4. In a remote control latch for automobile bodies, the combination of a latching unit provided with a sliding bolt, a remote actuator control unit therefor, which includes an actuator plate and a vertical rotary 125 spindle journaled therein, a draft bar member for providing a detachable and lost motion connection between the actuator and the sliding bolt, and motion translating means operatively connected to the draft bar for 130

converting the rotary motion of the vertical spindle to a reciprocating motion of the draft member.

5. In a rotary spindle latch, the combination of a plate, a rotary spindle journaled therein and provided with a crank shaft portion, a slide slidably supported by said plate and provided with a struck-out ear and an abutment, means for exerting a pressure on said rotary spindle to yieldingly hold the crank shaft portion in engagement with the struck-up ear, to prevent rattling.

6. In a remote control latch for automobile bodies, the combination of a latching unit provided with a sliding bolt and means for moving the same, a remotely located independent actuator unit comprising an actuator plate, a vertical rotary spindle journaled therein and a slide supported by said plate, means for providing a lost motion connection between the slide and the bolt, and means for exerting a pressure on said rotary spindle to yieldingly hold the crank shaft portion in engagement with said slide to prevent rattling and to prevent the slide from shifting back and forth.

7. In a remote control latch, the combination of a latching unit provided with a sliding bolt, and means for moving the bolt, a remotely located independent actuator comprising an actuator plate provided with a groove, a vertical rotary spindle journaled therein and a slide supported in the groove in said actuator plate, means for providing a lost motion connection between the sliding bolt and the slide of the actuator unit, and means for exerting a pressure on said rotary spindle to yieldingly hold the crank shaft portion in engagement with said slide to prevent rattling and to prevent the slide from shifting back and forth in the groove in the actuator plate.

8. In a latch, the combination of a sliding bolt, an actuator unit which includes a slide and a detachable connection between the sliding bolt and slide, said slide formed of a sheet metal stamping folded to provide an abutment, laterally projecting flanges and provided with pressed in ribs at the base of the abutment to strengthen the same, said slide also provided with a perforation in one of said lateral flanges for receiving one end of the detachable connection between the sliding bolt and slide.

9. In a latch, the combination of a sliding bolt, an actuator unit which includes an actuator plate having a groove therein, a slide supported in said groove and a connection between the slide and bolt, said slide formed of a sheet metal stamping folded and punched to provide an abutment and lateral projecting flanges one on each side of said abutment and arranged to be guided in the groove on the actuator plate, one of said lateral flanges having an intermediate por-

tion raised with respect to the other flange to provide clearance between the slide and bottom of the groove, and provided with a perforation in the raised portion of the flange to permit one end of the connection between the slide and bolt to be anchored between the slide and the bottom of the groove, the extreme edge of said flange bent down to form a foot on the level of the other flange arranged to be guided in said groove.

10. In a remote control latch for automobile bodies, the combination of a latching unit provided with a bolt retractable from the outside of the door, a remote control unit operable for retracting the bolt at a point remote from the latch fixture, and a draft connection between said bolt and remote control unit, and means laterally stressing said draft member for preventing rattling of the parts.

11. In a remote control latch for automobile bodies, the combination of a latching unit provided with a bolt retractable from the outside of the door, a remote control unit operable for retracting the bolt at a point remote from the lock fixture and a draft connection between said bolt and remote control unit, and means for placing said draft member under lateral stress to prevent rectilinear movement of the draft member and rattling of the parts.

12. In a remote control latch for automobile bodies, the combination of a latching unit provided with a sliding bolt and located on the latch board of the door, a remote control unit also located on the latch board on the inside of the door and including a vertical actuating spindle extending up through the garnish moulding of the door, a draft connection between said remote control unit and said latch, resilient means for holding said vertical spindle in normal position and to prevent rattling, and means contacting with said draft connection for preventing rattling thereof and of connected parts.

13. In a remote control latch for automobile bodies, the combination of a latch unit provided with a bolt retractable from the outside of the door, a reciprocable actuator unit positioned at a point remote from the latch bolt, a rigid draft member positioned on the inside of the door and connecting said remote actuator and the latch bolt, the connections between said draft member and the bolt and actuator member being of the pin and slot type, each pin being provided with a retaining head positioned at an angle to the normal line of movement of the draft member.

14. A remote control latch for automobile bodies, the combination of a latching unit provided with a bolt retractable from the outside of the door, a remote actuator unit and a rigid draft link positioned on the inside of the door and having a quickly detachable non-distortable hook connection with parts

of one of the said units, and also a connection with the other unit.

15. In a remote control latch for automobile bodies, the combination of a latching unit provided with a bolt retractable from the outside of the door, a remote actuating unit, and a draft link positioned on the inside of the door and having a quickly detachable connection with parts of one of said units and 10 also a connection with the other unit, the parts of said latch including the bolt, draft link, and remote actuator having their longitudinal axes normally in longitudinal alignment, the part of said draft link and the 15 part of said unit forming the quickly detachable connection being such that when the parts are in longitudinal alignment said connection will be maintained in fixed assembled relation, it being necessary to move one 20 of said parts including the draft link and said unit out of longitudinal alignment to effect assembly or disassembly of the parts.

In testimony whereof we have affixed our signatures.
